UNITED STATES PATENT OFFICE.

ARVID H. NERO, OF NEW BRITAIN, CONNECTICUT, ASSIGNOR TO THE ARROW ELECTRIC COMPANY, OF HARTFORD, CONNECTICUT, A CORPORATION OF CONNECTICUT.

ELECTRIC SWITCH.

Application filed March 26, 1920. Serial No. 368,961.

To all whom it may concern:

Be it known that I, ARVID H. NERO, a citizen of the United States of America, and residing at New Britain, in the county of 5 Hartford and State of Connecticut, have invented certain new and useful Improvements in Electric Switches, of which the following is a specification.

My invention relates to toggle switches, 10 and particularly to a switch of the type shown in my copending application Ser. No. 351,661, filed January 15, 1920, the object of my invention being to improve the latter in certain details of construction hereinafter 15 described or shown in the accompanying drawings, in which—

Fig. 1 is a plan view of a switch in which my invention is embodied in one form;

Fig. 2 is a longitudinal section there- 20 through;

Fig. 3 is a perspective of the switch frame;

Fig. 4 is a perspective of the carrying yoke;

Fig. 5 is a broken perspective of the switch bar;

Fig. 6 shows in broken plan and side elevation, a portion of the bridge piece of the switch bar; and

Fig. 7 shows in front and side elevation, 30 one of the legs of the switch bar.

In its main features the present switch is of the type shown in my application above referred to, and comprises an insulating body 10 of inverted cup shape apertured at 11 to permit the switch operating lever 12 to pass therethrough. The body 10 is closed at its open bottom by a detachable metal cover 13 having an insulating lining 35

14, both secured to the insulating body by the end bolts 15 passing therethrough and engaging a supporting yoke 16 by means of which the switch may be mounted in an outlet box or the like. Within the switch cham- 40 ber 17 are arranged the several switch terminals 18, secured in position by the several screws 19 passing through the top of the insulating body and taking into tapped lugs on the bases of the terminals. The termi- 45

nals are electrically connected to the wire terminal binding screws 20 by the stems of the latter, which pass down through the top of the body 10 and also engage in tapped holes in the bases of the switch terminals. Metal plates 21 are preferably ar- 50

ranged beneath the heads of the binding screws 20 in the wiring recesses 22 in order to afford a better mechanical and electrical connection with the lead wires.

In the form here shown the supporting 60 yoke 16 is extended the full length of the switch and is expanded at 23 midway of its length to overlie the top of the insulating body 10 on opposite sides of the aperture 11 for the switch lever. At this point the 65 yoke 16 is apertured at 24 and integral lugs 25 are struck down at the opposite margins of the aperture and pierced at 26 to receive the bearing pin 27 on which the switch lever 12 is mounted. This relieves the switch 70 frame from the strains incident to the operation of the switch lever to which the frame is subjected in the construction shown in my application above mentioned.

The switch frame is struck from sheet 75 metal and bent to shape. Its spaced side pieces 28 and 29 have offset lugs 30 at their upper edges which lie against the inner face of the top of the switch body and are secured in position by screws 31 passing there- 80 through and taking into tapped holes 32 in the lugs. Instead of using independent end pieces, as in my prior construction, which are riveted to the side plates, I now form the end stops by means of lugs 33 integral 85 with and extending at right angles to the side 28, and forming struts which space the sides 28 and 29 of the frame apart. As will be noted, the lugs are offset sufficiently 90 to abut against the face of the opposite side 29 of the frame.

The rocker 34 is pivoted on lugs 35 struck inward from the lower margin of the side pieces 28 and 29 of the frame. As in my previous construction the slots 36 formed 95 in the legs of the rocker receive operating lugs 37 at the lower end of the lever 12. The switch spring 38 hangs from the cross piece 39 at the top of the rocker and engages a tongue 40 struck from the bridge 100 piece 41 of the switch bar. The latter straddles the switch frame and rocks on bearing lugs 42 struck outward from the side plates 28 and 29 of the frame. The switch spring 38 is sufficiently tensioned to 105 hold the switch bar against the bearing lugs 32, thus enabling me to utilize notch bearings 43 in the ends of the bar. In order to permit the ready assembly of the parts, the legs 44 of the bar are offset at 45, and the 110

bearing notches 43 are extended through the offsetting shoulder 46, thus permitting the bearing lugs 42 to be introduced into the bearings 43 without spreading the yoke. 5 The metal struck from the end pieces 44 to form the bearing notch 43 is offset outward to form a tongue 47, which is utilized as a rivet to hold the contact wings 48 to the switch bar. The tongue 40 to which the 10 lower end of the spring 38 is attached is formed by slitting the bridge piece 41 and offsetting the tongue 40 upwardly therefrom to facilitate the insertion of the end of the spring. On opposite sides of the tongue 40 15 the bar is not only offset downward in opposition to the tongue 40, but also spread in opposite directions to afford a generous opening for the eye of the end of the spring. The modifications of construction above 20 described facilitate the construction and assembly of the switch parts without in any way impairing the operation of the switch. Detail variations of construction and shape of the parts will readily occur to those skilled in the art without departing from 25 what I claim as my invention.

I claim—

1. In an electric switch, an insulating body, a supporting yoke therefor having an 30 enlarged area intermediate its ends and apertured to accommodate a switch-operat-

ing lever, lugs offset toward the insulating body at opposite sides of said aperture, in combination with a switch-operating lever passing through said aperture and having 35 legs spaced to bear against and be guided by said lugs, together with means for pivoting said lever on said lugs.

2. In an electric switch, a one-piece switch frame struck from sheet metal and comprising spaced side plates joined by marginal bridge straps at one end and having offset securing lugs at the opposite end of the side plates, together with strut lugs integral with one of said side plates and extending from 40 the side edges thereof to the opposed side plate, in combination with oscillating members pivoted on said plates, one of said oscillating members working between the bridge straps, and the other of said oscillating members working between said offset strut lugs and having its travel limited 45 thereby.

3. In an electric switch, a switch yoke having a lug offset therefrom to form an 50 open bearing slot, together with a switch blade carried by said yoke and secured thereto by said offset lug.

In testimony whereof I have signed my name to this specification.

ARVID H. NERO.
